UNITED STATES PATENT OFFICE

EDGAR SCOFIELD, OF NEW YORK, N. Y., ASSIGNOR TO ANCHOR CAP & CLOSURE CORPORATION, OF LONG ISLAND CITY, NEW YORK, A CORPORATION OF NEW YORK

CONTAINER

Application filed November 30, 1927. Serial No. 236,603.

The present invention relates to containers and more particularly to paper or fibrous containers with a metallic cap attached thereto.

Paper cartons have been used extensively for packing plastic material such as ice cream and for distribution of liquids such as milk, cream, sodas and the like. Considerable difficulty has been encountered in the use of these due to the fact that the upper part of the cartons becomes weakened or deformed during the filling operations and the covers do not fit properly. They are difficult to apply and are not liquid-tight when applied. In making the carton sufficiently heavy to overcome, to any extent, these difficulties, the amount of material required is increased greatly and the cost of the carton becomes extremely high and practically prohibitive.

Attempts have been made to adapt the containers for screw caps by forming screw threads in the fibrous material while it is in a semi-plastic condition. Attempts have also been made to apply screw bands to the containers while in a plastic state but such application weakens the container at its upper part and also thins it considerably. In either case the application or removal of the screw cap is likely to shear the carton adjacent the threads. In addition the metal bands frequently become loose and slip from the cartons.

The present invention overcomes these difficulties by providing a metallic collar for strengthening the upper part of the carton and by securely attaching the collar to the carton without weakening it at any point. The collar preferably has suitable screw threads or other engaging means for the accommodation of metal caps. The collars may and preferably are applied to the cartons in their completed state, that is, after the fibrous material has become hardened and is waxed.

An object of the invention is to improve the present paper or fibrous cartons used in carrying liquids and plastic products.

Another object is to provide a paper or fibrous container reinforced at its upper end to which a metallic cap may be readily applied.

Another object of the invention is to pre-

vent deformation of the upper ends of fibrous containers during filling thereby facilitate the application of caps and covers thereto.

A further object of the invention is to provide an inexpensive paper carton to which a metallic screw cap may be readily applied. 55

Other and further objects of the invention will be obvious upon an understanding of the illustrated embodiment about to be described or will be evident from the following 60 description; and various advantages not referred to herein will occur to one skilled in the art upon employment of the invention in practice.

A preferred embodiment of the invention 65 has been chosen for purposes of illustration and description and is shown in the accompanying drawings, in which

Fig. 1 is a view of the parts in unassembled relation with the cap and collar shown in 70 section;

Fig. 2 is a partial sectional view of the collar resting upon the container before attachment thereto;

Fig. 3 is a fragmentary sectional view showing the collar attached to a container; and 75

Fig. 4 is an elevational view of the upper part of the container partly in section showing the completed package.

Referring to the drawings, there is shown 80 a container 1 preferably formed of fibrous material such as paper and the like in the usual manner. The material may be a single piece of cardboard or several thicknesses of paper suitably attached to each other. The 85 material may be waxed, if desired. Such containers have been and are now used for liquids and plastic material generally with a slip cover telescoped about the upper end thereof. 90

A collar 2 is provided having an inwardly extending flange 4 at its upper end and a rolled edge 5 at the bottom thereof. The cylindrical portion of the collar is provided with 95 screw thread 6 or with any other suitable means for engagement with the cap. The minimum internal diameter of the collar is sufficient to permit the collar to be telescoped about the upper end of the container 1 as 100

shown in Fig. 2 without deformation of the container. Preferably the screw threads on the collar make no indentation whatever in the container but telescope loosely thereabout.

5 In this way there is no weakening whatever of the upper part of the container.

The inwardly extending flange 4 is rolled downwardly and inwardly toward the wall of the container so that the free edge of the 10 collar engages the wall of the container slightly below the edge thereof and rolls into an interlocking relation as shown in Fig. 3. The entire grip of the collar upon the container is at the upper peripheral edge thereof. It will be noted that the free edge of the 15 collar presses the wall of the container tightly against the cylindrical part of the collar. In addition the interlocked part or free edge of the container is pressed tightly between 20 the rolled portion 7 and the cylindrical part of the collar. In this way, a very firm grip is attained while permitting the lower part of the collar to fit loosely upon the container. In addition, the free raw edge of the collar is 25 rolled downward, outwardly and upwardly to interlock with the free edge of the fibre container and to substantially conceal the raw edge of the metal. This eliminates any tendency for this uncoated portion of the metal to 30 corrode from contact with the contents of the container. The collar is preferably applied to a fully formed container with the material thereof in its final hardened or waxed condition. Operations thereupon in such a 35 erate with the corresponding screw threads 6 thereof where the collar is applied in the manner set forth. Hence the completed container is fully capable of withstanding any shearing stresses that may be applied, even when the 40 container is made much thinner than heretofore.

A screw cap 8 is provided of any suitable form, here shown, having a cover portion 9 and a depending cylindrical skirt 10 having 45 the screw threads 11 therein adapted to cooperate with the corresponding screw threads 6 on the collar 2. The upper part of the skirt is knurled or corrugated as shown at 8 to strengthen this part of the cap and also to facilitate manual gripping thereof. The bottom of the cap is formed with a rolled edge 14 which strengthens this portion of the cap and prevents contact with the raw edge thereof. The length of the skirt of the cap is such that 55 the rolled edge 14 abuts against the edge 5 of the collar to limit the downward, telescoping movement of the cap about the collar and to provide a resilient engagement therebetween, whereby a firm locking relation is obtained 60 between the two. This facilitates the application of the cap and the removal thereof and minimizes adherence to the collar.

It will be seen that the present invention 65 provides an inexpensive container to which metallic caps may be readily applied without

danger of accidental removal thereof. The containers or cartons may be made of thinner material due to the fact that the metallic collar reinforces the upper edge and prevents contact of the liquids therewith and eliminates deformations at this part of the container. The metallic collar can be readily made of a definite size and because of its strong character will resist the stresses placed upon it when being filled with plastic material such as ice cream. It will retain its proper shape so that a screw cap may be readily applied thereto. The attachment of the collar to the container is such that the container is not weakened in any way and the material of the upper part thereof is not reduced in thickness. The rolled edge on the cap prevents contact with the raw edge thereof and in addition provides a springy engagement between the collar and the screw cap by means of which a more perfect attachment is attained. Further, the container is strong and durable in character and fully capable of withstanding the rough usage to which it may be subjected.

As various changes may be made in the above embodiment without departing from the spirit of the invention, it is to be understood that all matter herein is to be interpreted as illustrative and not in a limited sense. It is to be understood also that the term "paper" used herein is intended to include any form of fibrous material.

Having thus described my invention, I 100 claim:

1. In a device of the class described, the combination of a paper carton, a threaded metal collar adapted to receive a screw cap telescoped about the upper end of said carton, said collar having a continuous upper edge secured in position by an interlocking inturned folding engagement of the upper edge of the collar with the upper periphery of the carton whereby only the upper peripheral edge of the carton is deformed in the application of the collar to the container and the raw edge of the metal collar is concealed.

2. In a device of the class described, the combination of a collar adapted to be attached to the end of a container, an inturned flange at the upper part of the collar rolled into continuous interlocking engagement with the upper peripheral edge of the container, the lower edge of the collar being rolled to strengthen same and to form an abutment for a screw cap and a screw cap attached to said collar, said screw cap having a rolled lower edge engaging the rolled lower edge of the collar and a knurled upper part.

3. In a device of the class described, the combination of a paper carton and a threaded collar attached to the upper end of said carton without rupturing the side wall thereof, the upper part of said collar having a continuous edge rolled downwardly and inwardly

into interfolded locking engagement with the upper peripheral edge of the carton to hold same in position and to protect the raw edge of the metal, thereby to prevent rusting.

5 4. In a device of the class described, a paper carton, a threaded collar attached to the upper end of said carton without rupturing of the side wall thereof, the upper part of said collar having a continuous edge rolled

10 downwardly and inwardly into continuous interfolded engagement with the upper periphery of the carton to hold same in position, the lower edge of said collar being rolled to strengthen same and to form an abutment, 15 and a screw cap threaded into engagement with said collar with the lower edge of the cap in engagement with the rolled edge of the collar.

5. In a paper carton, the combination of a 20 fibre carton and a threaded metal collar telescoped about the upper end of said carton, said collar having a continuous upper edge rolled inwardly and downwardly into locking engagement with the upper end of the 25 carton, the raw edge of the metal of the collar being substantially concealed and to protect against rust by the interlocking engagement with the carton, the remaining portions of the collar being telescoped loosely 30 about the container.

6. In a device of the class described, the combination of a fibre carton, a threaded metal collar having a narrow inturned flange having a continuous free edge, said flange being 35 rolled downwardly and inwardly to interlock with the free edge of the carton and to conceal the raw edge of the metal without rupturing the wall of the fibrous container.

7. A package comprising a carton, a 40 threaded cylindrical collar portion adapted to be telescoped about the open end of the carton with a continuous inturned edge extending over the free edge of the carton, said inturned edge being rolled downwardly and 45 outwardly into interfolded locking engagement with the carton without rupturing the fibrous carton, and a sheet metal screw cap secured to said carton by being threaded into engagement with said collar.

50 8. In a device of the class described, the combination of a paper container, a metallic collar telescoped about the upper end thereof, the upper edge of said collar being continuous and rolled into continuous folded relation with the inner side wall of the upper 55 peripheral edge of the container to conceal the raw edge of the metal and to protect it against rust and to form a strong grip with the container, the lower edge of said collar 60 on the interior of the container being rolled to strengthen same and to form an abutment for a closure cap applied thereto.

9. In a device of the class described, the 65 combination of a paper carton and a threaded metallic collar telescoped about the upper

end of said carton having a continuous upper edge, said continuous upper edge of the collar being folded inwardly, downwardly and outwardly to grip firmly the upper periphery of the carton on the inner wall thereof to retain 70 the collar in position and to protect the raw edge of the metal against rust, the lower edge of the collar being rolled outwardly and upwardly to conceal the raw edge thereof.

10. In a paper carton, the combination of a 75 fibre container, a threaded metal collar telescoped about the upper end of said container, said collar having a continuous upper edge rolled inwardly and downwardly into continuous locking engagement with the inner 80 wall at the upper end of the container, the raw edge of the metal of the collar being concealed and protected against rust by the interlocking engagement with the container, the lower edge of said collar being rolled 85 outwardly and upwardly to protect the raw edge of the metal and to form a stop for a closure cap, and a screw cap mounted upon said collar closing the container and engaging the rolled edge on the collar as an abut- 90 ment.

11. In a device of the class described, the combination of a fibre carton, a threaded metal collar having a narrow inturned flange with a continuous free edge, said free edge 95 being rolled downwardly and outwardly into contact with the inner side wall of the carton to conceal the raw edge thereof and to interlock with the free edge of the carton to protect the raw edge of the metal without rupturing the walls of the fibre container, the lower edge of said collar being beaded to 100 form an abutment for a closure cap, and a screw cap applied to said collar and abutting said beaded edge.
